HYDRAULIC CONTROL VALVE WITH
VOID CONTROL MEANS

Francis H. Tennis, Milwaukee, Wis., assignor to Hydraulic
Unit Specialties Company, Town of Pewaukee, County
of Waukesha, Wis., a corporation of Wisconsin

Filed May 2, 1962, Ser. No. 191,868

7 Claims. (Cl. 137—596)

This invention relates to hydraulic control valves of the type wherein a valve element is shiftable in a bore in a valve body to either of two defined operating positions, to selectively govern the direction of operation of a double acting hydraulic cylinder or similar reversible hydraulic motor; and the invention refers more particularly to anti-cavitation or void control means in a hydraulic control valve of that nature.

A hydraulic control valve of the type hereunder considered comprises a body having therein a pressure fluid inlet connectable with a pump or other source of hydraulic fluid under pressure, a return fluid outlet connectable with a reservoir of the like, and one or more spool bores, each having a pair of service passages leading therefrom to motor ports in the body that are connectable with the ports of a reversible hydraulic motor. In each spool bore there is a spool that is manually slidable in opposite directions from a neutral position to one or the other of a pair of operating positions. When the spool is in its neutral position it permits pressure fluid to flow from the inlet to the outlet for return to the reservoir; and in each of its operating positions the spool directs pressure fluid from the inlet to one of the service passages while communicating the other service passage with the outlet so that return fluid from a motor governed by the spool is sent back to the reservoir.

It often happens that a double acting hydraulic cylinder is employed to drive a mechanism that is subjected to substantial gravity or inertia loads which effect more rapid movement of the mechanism in one or both directions than it can be propelled by its hydraulic cylinder.

Under these conditions, where the cylinder is driven by the load rather than driving it, the rate at which hydraulic fluid is supplied to the cylinder by the hydraulic pump may be insufficient to fill the void in the cylinder left by its rapidly moving piston, with undesirable consequences that are well known to those skilled in the art.

To prevent drawing of a void under these circumstances it has been customary to provide such hydraulic systems with so called anti-cavitation or void control check valves which are normally closed but which open when the hydraulic motor is driven by its load and the piston is tending to draw a void, and which then permit return fluid from one end of the cylinder to be transferred back to its other end along with the fluid supplied thereto by the pump.

Such void control or anti-cavitation valves have ordinarily been incorporated in the body of the control valve by which the hydraulic mechanism is governed, and heretofore it has been the usual practice to provide one such void control valve for each of the service passages in the control valve body at which a void might be drawn under operating conditions. Thus in cases where a number of control valve sections were ganged or stacked in a single assembly, for controlling several double acting cylinders from one location, there could be as many void control check valves in the assembly as service passages, with each pair of void control valves located in the valve body section that contained the spool with which the check valves were associated.

By contrast, it is a general object of the present invention to simplify the construction of spool type control valves having void control means embodied therein, and

2

to reduce the cost of such valves, by providing a single void control check valve which serves all of the service passages in a control valve assembly, whether there be only two such service passages, associated with a single valve spool, or a substantially large number of them, associated with a plurality of valve spools as in a stacked or sectional valve.

It is another object of the present invention to simplify the construction of hydraulic control valves, whether having bodies cast in one piece or of the so called stacked or sectional type, and to minimize the cost of such valves by incorporating the void control means for the valve assembly in a manifold section having a chamber that is common to the service passages governed by all of the control spools of the valve.

It follows that it is another object of the present invention to make it possible to incorporate into the inlet section of a sectional control valve a combined pressure relief and vacuum relief valve of the type shown, for example, in the copending application of Francis H. Tennis and Donald G. Bethke, Serial No. 186,906, filed April 12, 1962, for Combined High Pressure Relief and Void Control Valve, now Patent No. 3,112,763, so that the one composite valve performs all of the pressure relief and anti-cavitation functions for the entire valve assembly, serving all of the motor ports in the valve body, however, many there may be.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiments of the invention constructed according to the best modes so far devised for the practical application of the principles thereof, and in which:

FIGURE 1 is a vertical sectional view of a sliding spool type of hydraulic control valve of sectional construction, comprised of two control sections, and incorporating the void control means of this invention;

FIGURE 2 is a fragmentary sectional view on an enlarged scale of a portion of the valve shown in FIGURE 1;

FIGURE 3 is a horizontal sectional view taken on the plane of the line 3—3 in FIGURE 1; and

FIGURE 4 is a fragmentary vertical sectional view of a modified embodiment of the invention incorporating the combined high pressure and low pressure relief valve of the aforesaid application.

Referring now more particularly to the accompanying drawings, the numeral 5 designates generally the body of a hydraulic control valve which, though not essential to the invention, is illustrated as being of sectional construction. It comprises in general an inlet manifold section 6, an exhaust manifold section 7, and a plurality of individual control or spool sections 8 and 9 which are assembled in stacked relationship with one another and with the inlet and exhaust sections, the latter being at opposite ends of the stack. Obviously the two spool sections shown are illustrative, since there might be only one such section in the stack, or any number of them. The two spool sections 8 and 9 may be substantially identical with one another, and each has a bore 11 therethrough in which a spool or valve element 12 is slidable in opposite directions from a neutral position, shown in FIGURE 3, to either of two operating positions at which the spool effects operation in one direction or the other of a double acting hydraulic cylinder or a similar reversi-

ble hydraulic motor (not shown) connected with motor ports 13 and 14 in the spool section body.

Hydraulic pressure fluid from a source thereof such as a pump (not shown) enters an inlet chamber 18 in the inlet section 6 through an inlet port 16. When the several spools are all in their neutral positions, pressure fluid can flow from the inlet chamber 18 to a return fluid chamber 20 in the exhaust manifold section 7 by way of an open center passage 21 that extends through the several body sections, intersecting the bores 11 therein. The return fluid chamber opens to an outlet port 22, which in this case is shown as being in the exhaust manifold section and which is connectable with a reservoir (not shown) or the like.

When any one of the spools 12 is moved to an operating position, it blocks the open center passage 21 and directs pressure fluid from the inlet chamber 18 into one or the other of a pair of service passages 27 and 28 that communicate the spool bore with the motor ports 13 and 14 respectively. In this case such diversion of fluid from the inlet chamber to a motor port is shown as being provided for by a feeder passage 23 that opens from the inlet chamber 18 and extends through the several spool sections of the body, and branched feeder passages 24 and 25 in each spool section which communicate the feeder passage with the spool bore. Those skilled in the art will recognize that the provision of the feeder or supply passage 23 just described enables parallel operation of motors governed by the spools 12; and it will be appreciated that this arrangement is merely illustrative, as the branched feeder passages can be connected with the open center passage 21 to be supplied with pressure fluid therefrom in a series-parallel type valve.

At the same time that the spool directs pressure fluid to one of its associated service passages it communicates the other service passage with a branched exhaust passage 30 which communicates with a return fluid passage or exhaust header 29 that extends through the several valve body sections and opens at one end to the return fluid chamber 20, whence such return fluid can of course pass to the outlet 22 and a reservoir connected therewith.

At its other end the return passage 29 has a portion 31 that extends into the inlet section 6 of the valve body, and which is branched, as at 33 and 34, for communication with the inlet chamber 18. However, communication between the inlet chamber and the return passage is normally blocked by a pressure relief valve 36 which controls the branch 33 and by a void control check valve 37 which controls the branch 34.

The pressure relief valve 36 can be of a conventional type and needs no description here. Suffice it to say that it is responsive to pressure of fluid in the inlet chamber 18, and when such pressure exceeds a predetermined value the relief valve unseats and permits pressure fluid to flow from the inlet chamber into the return passage 29 by way of the branch 33. The short passage comprising the exhaust header branch 33 is of course formed with a suitable annular seat against which the relief valve element is normally engaged under bias.

The void control valve 37 can likewise be of a known type, comprising a check valve that opens when pressure of fluid in the return passage 29 exceeds that of fluid in the inlet chamber 18, as may happen when one of the spools 12 is in an operative position and a hydraulic motor governed thereby is being driven by its load in such a manner as to create a demand for pressure fluid greater than can be satisfied by the pump alone. Under such conditions return fluid can flow from the return passage, past the check valve 37, to the inlet chamber 18 where such return fluid supplements the pressure fluid that the pump is delivering to the service passage then communicated with the inlet chamber.

In this case the void control check valve is shown as a poppet having an enlarged head 40 and a coaxial stem portion 41 which is slidably guided in an inwardly opening

well 42 formed in a plug 43 that is threaded into the wall of the inlet section. The branch 34 of the return passage with which the void control valve cooperates is an axial extension of the return passage and opens into the inlet chamber 18 through an annular valve seat 44 which faces away from the return passage, and with which the head of the poppet is normally engaged.

If the valve body 5 is mounted in the position shown in FIGURE 1, with the inlet section 6 uppermost and the exhaust header 29 extending substantially vertically downwardly therefrom, gravity can be relied upon to bias the check valve poppet onto its seat. Preferably, however, the stem portion of the valve element has a well therein in which a light coiled compression spring 45 is confined, that reacts between the bottom of the well 42 in the plug 43 and the valve element to insure that the poppet will be biased toward its seat in any attitude of the valve body.

To insure dependable operation of the check valve 37 the void control mechanism preferably includes a relief or back pressure valve 47 which at all times tends to maintain return fluid in the exhaust header 29 at a uniform pressure somewhat higher than that of fluid in the return fluid chamber 20 and the reservoir or the like connected therewith. The valve 47 can be, as illustrated, a dual function valve of the type disclosed in the copending application of Francis H. Tennis, Serial No. 153,415 filed November 17, 1961, for Pilot Operated Pressure and Vacuum Relief Valve, now Patent No. 3,100,503. Details of that valve unit can be found in said copending application, but briefly, it comprises (see FIGURE 2) a body 91 in which a plunger-like outer poppet 92 is axially slidable toward and from engagement with a seat 93 that faces toward the return fluid chamber 20 and coaxially surrounds the outlet of the exhaust header 29. The outer poppet, which is a low pressure responsive valve element, has an axially extending but eccentric passage 94 therein that communicates the exhaust header 29 with the cylinder space in the valve body 91 which is behind said poppet. A coiled compression spring 95 cooperates with fluid in the body 91 behind the outer poppet to urge the latter towards its seat 93. Pressure of fluid in the return fluid chamber 20 is exerted upon an annular forwardly facing surface 96 on the outer poppet, spaced behind its seat engaging surface, and when such pressure exceeds that in the exhaust header 29 the outer poppet moves away from its seat 93. This condition could occur in a situation where there was an extreme tendency to draw a void in one of the service passages, so that return fluid from the other service passage plus pressure fluid supplied by the pump would be insufficient to supply void control requirements, and in that event fluid from the return fluid chamber 20 and a reservoir connected therewith could flow back into the exhaust header 29 and thence to the service passage at which the void was being drawn, to supply the deficiency.

Slidable in the outer poppet is an inner pilot poppet 97 which normally blocks flow of fluid through a vent passage in the outer poppet and which is biased forwardly relative to the outer poppet by a compression spring 98. The vent passage is defined by the axial passage 94 in the outer poppet, a coaxial bore 99 in the outer poppet which the passage 94 intersects and which opens rearwardly to a counterbore 100 in which the inner poppet is located, and one or more lateral bores 101 opening radially from the counterbore to the return fluid chamber. The seat for the inner poppet is defined by the junction of the bore 99 with the counterbore 100, and the inner poppet is biased toward said seat with an adjustably variable force by reason of the fact that the spring 98 reacts against a spring seat 102 that is threaded into the rear of the outer poppet and is adjustable axially by means of an adjusting mechanism 103 described in the aforesaid copending application Serial No. 153,415.

The inner poppet is moved off to its seat in response to fluid pressure above a predetermined value in the exhaust header 29, which pressure is manifested upon a small plunger 104 that is freely movable axially in the bore 99. So long as such fluid pressure exceeds the value for which the pilot spring 98 is adjusted, the plunger will hold the pilot poppet 97 unseated, permitting fluid to be vented from behind the outer poppet through the vent passage 94, 99, 100 and 101; and such venting of fluid from behind the outer poppet permits the latter to be moved off of its seat in response to the pressure of fluid in the exhaust header 29 manifested upon its front end. When the valve unit is thus effecting high pressure relief, with the small plunger 104 in its rearward position, said plunger partially blocks the intersection of the bore 99 and the eccentric passage 94, restricting flow of fluid into the rear portion of the body 91 and thus preventing chattering of the outer poppet. It will be understood that the force of the pilot spring 98 is set to maintain a constant pressure differential between the fluid in the exhaust header 29 and fluid in the return fluid chamber 20, of a value small enough not to interfere with operation of motors connected with the control valve, but sufficient to insure rapid and dependable opening of the void control check valve 37.

Instead of the dual function valve 47, the outlet of the exhaust header could be a restricted orifice, in which case back pressure would be manifested upon return fluid in the exhaust header 29 only at high flow rates, such as occur when a void tends to be drawn in one of the service passages. In either event the flow restricting means causes the check valve 37 to be unseated before an actual void can be drawn in the service passage to which pressure fluid is being directed by the valve spool.

In the embodiment of the invention illustrated in FIGURE 4 the void control means is incorporated in a composite valve assembly 51 that also provides the high pressure relief valve, and which is of the type disclosed in the aforesaid application of Francis H. Tennis and Donald G. Bethke, Serial No. 186,906, now Patent No. 3,112,763. In this instance the exhaust header 29 is communicable with the inlet chamber 18 through a single branch passage 133 that is controlled by the composite valve assembly 51 and which is of course normally closed by said valve assembly. In other respects the valve illustrated in FIGURE 4 can be identical with that shown in FIGURE 1.

The valve assembly 51 comprises a body 52 which is open at its front and provides a cylinder at its rear in which a tubular low pressure poppet 53 is slideable toward and from engagement with a seat 54 formed coaxially with the branch passage 133. The low pressure poppet is biased toward the seat by means of a coiled compression spring 55 that reacts between said poppet and the valve body 52. At its front the low pressure poppet is formed with a forwardly facing shoulder 59 against which the pressure of fluid in the exhaust header is manifested, and when pressure of fluid in the inlet chamber 18 falls below that of fluid in the exhaust header 29, the rear portion of the cylinder is evacuated through the bore in the low pressure poppet, allowing the latter to move rearwardly off of its seat in response to the force exerted upon shoulder 59 by fluid in the exhaust header.

The high pressure relief valve comprises a tubular high pressure poppet 61 coaxially slideable in the low pressure poppet and having a stem portion 62 slidably guided in the rear portion of the low pressure poppet and an enlarged head portion 63 engageable with a coaxial rearwardly facing annular seat 64 at the front of the low pressure poppet. The high pressure relief passage comprises the front portion 65 of the bore in the low pressure poppet and radial ports 66 in the side of the low pressure poppet, behind the seat 64 therein, that open from its bore to the exhaust header 29. The high pressure poppet is normally biased into engagement with its seat 64 by means of a coiled compression spring 67 encircling its stem por-

tion and reacting between its head and the low pressure poppet, but when pressure in the inlet chamber 18 exceeds a high value determined by the biasing force exerted by said spring the high pressure poppet is moved off of its seat, permitting pressure fluid to flow through the ports 65 and to the exhaust header.

For a more detailed description of the valve assembly 51 reference can be made to the aforesaid copending application.

It will be evident that a valve like the above described dual function valve 47 could be used in place of the last described composite valve assembly 51, and in that event the pilot spring 98 would of course be adjusted to a higher relief value, sufficient to maintain normal system pressure in the inlet chamber 18. The provision of a composite or dual function valve to control communication between the inlet chamber and the exhaust header has the obvious advantage of compactness, but has the further important advantage that its low pressure poppet moves off of its seat in a direction counter to that in which it permits fluid to flow. Such action of the low pressure poppet permits substantially unrestricted flow of fluid, as contrasted with the poppet of a more conventional check valve, which moves in the direction in which it permits flow to take place and which presents a substantial restriction to the flow that it permits because fluid is always compelled to flow around it and also around any spring that may be biasing it toward its seated position. The importance of this feature will be apparent when it is considered that when a void is developing in a service passage the pressure differential between the inlet chamber and the exhaust header is relatively low, even with the flow restrictor 47, and hence any substantial restriction presented by the check valve means would interfere with the desired free flow.

It will be evident that the void control means of this invention is applicable to hydraulic control valves which are not of the sectional type herein illustrated and described, although it is particularly advantageous in valves of that type because it enables but one check valve in the inlet section to serve any number of motor ports in the valve body, eliminating the need for pairs of check valves in the individual spool sections.

From the foregoing description taken together with the accompanying drawings it will be apparent to those skilled in the art that this invention provides void control or anti-cavitation means in a hydraulic control valve of the sliding spool type whereby a single check valve accommodates each and every one of the service passages in the valve body, permitting a valve incorporating the invention to be manufactured at lower cost and with greater facility than previous valves of comparable type.

What is claimed as my invention is:

1. A sectional control valve of the type comprising an inlet section having an inlet chamber into which pressure fluid from a source thereof can be introduced, a return fluid manifold communicated with an outlet, and at least one control section confined between the inlet section and the return fluid manifold, of the type in which a spool is slideable to each of a pair of operating positions to communicate either of a pair of service passages in the control section with a supply passage therein that connects with the inlet chamber, while communicating the other service passage with a return passage in the control section, said valve being characterized by the following:

- (A) that all of the return passages are connected to a common exhaust header having one end communicating with the return fluid manifold and which extends through each control section crosswise of the spool therein;
- (B) that the other end of the exhaust header is communicable with the inlet chamber through a pressure relief valve which normally blocks communication between the inlet chamber and said exhaust header, but is responsive to pressure of fluid in the inlet

chamber in excess of a predetermined value to open and permit flow of fluid therefrom to the exhaust header; and

(C) that said other end of the exhaust header is also communicable with the inlet chamber through a void control check valve which cooperates with the pressure relief valve to normally block communication between the inlet chamber and the exhaust header, but is responsive to pressure of fluid in the exhaust header which exceeds that of fluid in the inlet chamber to open and permit such communication so that whenever a control spool is in one of its operating positions and the pressure of return fluid from the service passage then communicated with the exhaust header exceeds the pressure of fluid in the inlet chamber, fluid can flow from said last named service passage to the inlet chamber via the exhaust header for flow to the other service passage along with pressure fluid entering the inlet chamber from a source.

2. A control valve of the type having a body in which there are a plurality of spool bores, each communicated with a pair of service passages, and a spool slideable in each bore to either of a pair of operating positions at each of which the spool directs pressure fluid from an inlet chamber in the valve body to one of the service passages associated with its bore and directs return fluid from its other associated service passage to return passage means in the body leading to an outlet therein, said control valve being characterized by: said return passage means comprises an exhaust header common to the service passages of all the bores, and extending crosswise of the bores; a unitary valve mechanism governing a void control passage in the valve body that connects one end of the exhaust header with the inlet chamber, said valve mechanism providing a check valve controlling direct communication between the inlet chamber and the exhaust header and preventing such communication as long as pressure of fluid in the inlet chamber exceeds that of fluid in the exhaust header but responsive to pressure of fluid in the exhaust header which exceeds that in the inlet chamber to open and permit return fluid from any service passage then communicated with the header to flow to the inlet chamber and thence to any service passage to which pressure fluid is then being directed, so that a single void control check valve serves all service passages in the valve body, and said mechanism also providing a normally closed high pressure relief valve which opens to establish communication between the inlet chamber and the exhaust header through said void control passage, in response to an abnormally high pressure condition in the inlet chamber.

3. A control valve of the type having a body in which there are a plurality of spool bores, each communicated with a pair of service passages, and a spool slideable in each bore to either of a pair of operating positions at each of which the spool directs pressure fluid from an inlet chamber in the valve body to one of the service passages associated with its bore and directs return fluid from its other associated service passage to return passage means in the body leading to an outlet therein, said control valve being characterized by: a single check valve in a void control passage in the valve body, controlling direct communication between the inlet chamber and the return passage means and preventing such communication as long as pressure of fluid in the inlet chamber exceeds that of fluid in the return passage means but responsive to pressure of fluid in the return passage means which exceeds that in the inlet chamber to open and permit return fluid from any service passage, then communicated with the return passage means to flow to the inlet chamber and thence to any service passage to which pressure fluid is then being directed, so that the single void control check valve serves all service passages in the valve body; said return passage means comprising an exhaust header in the body having one end opening into the inlet chamber

and its other end communicating with the outlet, the check valve being located at the first designated end of the header; and further characterized by means at said other end portion of the header to restrict communication with the outlet so that pressure in the header will rise quickly as soon as return fluid from any one of the service passages flows thereto at an abnormally high rate, thus insuring prompt unseating of the check valve.

4. A control valve of the type having a body wherein there is a spool bore and a spool slideable in the spool bore to either of a pair of operating positions at each of which the spool directs pressure fluid from an inlet chamber in the valve body to one of a pair of service passages in the valve body and directs return fluid from the other service passage to a return passage in the body leading to an outlet therein, said control valve being characterized by:

(A) the return passages lead to the outlet through a common exhaust header that has one end connected with the inlet chamber, and which header extends through the body at a location to one side and crosswise of the spool bore;

(B) valve means in the body controlling communication between the exhaust header and the inlet chamber, said valve means including

(1) high pressure relief valve mechanism which is normally closed but opens whenever the pressure of fluid in the inlet chamber rises to an abnormally high value to allow fluid to flow from the inlet chamber directly to the exhaust header,

(2) and normally closed low pressure relief valve mechanism that opens whenever the pressure of fluid in the inlet chamber drops to a value below that of fluid in the exhaust header;

(C) and means affording restricted communication between the exhaust header and the body outlet.

5. A control valve of the type having a body with a valve element movable therein to each of a pair of operating positions to communicate either of a pair of service passages with fluid supply means in the body and to communicate the other service passage with an exhaust outlet in the body, characterized by:

(A) means comprising a combination exhaust header and void control passage for communicating both the service passages and the fluid supply means with the exhaust outlet;

(B) a normally closed pressure responsive void control valve in the body controlling communication between the exhaust header and the fluid supply means, said void control valve being adapted to open in either operating position of the valve element to enable exhaust fluid from the service passage then communicated with the exhaust header to flow to the fluid supply means whenever the pressure of such exhaust fluid exceeds that of fluid in the fluid supply means;

(C) said exhaust header communicating with the fluid supply means at a zone of the latter upstream from the movable valve element; and

(D) means in the exhaust header downstream from its zones of communication with the service passages providing a restriction to flow of exhaust fluid to the exhaust outlet.

6. The control valve of claim 3, wherein said last designated means comprises a pressure sensitive valve device which is biased toward an extreme restricting position but opens to a less restricting position in response to rising pressure in the exhaust header.

7. The control valve of claim 4, wherein said last named means comprises

(1) high pressure relief valve mechanism which is normally closed but which opens whenever the pressure of fluid in the exhaust header rises to a predetermined desired value to allow fluid to flow from the header to the outlet,

(2) and low pressure relief valve mechanism which is

normally closed but opens whenever the pressure of fluid in the exhaust header drops to a value below that of fluid at the outlet, to allow fluid to flow from the outlet to the header.
